UNITED STATES PATENT OFFICE.

WILLIAM W. BIRNSTOCK, OF YORK, PENNSYLVANIA, ASSIGNOR TO HENCH & DROMGOLD COMPANY, OF YORK, PENNSYLVANIA.

NOZZLE-HEADER FOR BOTTLE-WASHING MACHINES.

1,349,144.

Specification of Letters Patent. Patented Aug. 10, 1920.

Application filed September 25, 1919. Serial No. 326,269.

To all whom it may concern:

Be it known that I, WILLIAM W. BIRNSTOCK, of the city and county of York, in the State of Pennsylvania, have invented 5 a new and useful Improvement in Nozzle-Header for Bottle-Washing Machines, of which the following is a specification.

My invention relates to that class of bottle washing machines in which crates containing the bottles to be cleansed, rinsed and sterilized are fed along, in inverted position, over a series of tanks, halting for a stated period over each tank to subject the bottles contained in the crates to the action 10 of the liquid appropriate to this tank, there being associated with each tank, a header carrying the nozzles from which the cleansing fluid is ejected, the bottles contained in each crate being properly centered relatively to the header nozzles to receive in 15 their open mouths the jets from the nozzles in the header below. The open bottom crates, which are of a standard size, are divided internally by skeleton partition structures or grids into cells for the individual bottles contained in the crates, which cells will vary in size and number according to the size of the bottles—as for example if intended to hold quart bottles, the crate will 20 have twelve cells arranged in rows of three crosswise and four lengthwise of the crate, while for pints, there will be in a crate of the same dimensions twenty cells in rows of four crosswise and five lengthwise of the 25 crate. Consequently the header must carry a separate set of nozzles for each size of bottle the crate contains—one set of twelve nozzles for use in connection with quart bottles, and another set of twenty nozzles for use in connection with pint bottles, either of which sets of nozzles may be called 30 into action to the exclusion of the other according to the number and size of the bottles contained in the crate. My invention 35 consists of a novel, inexpensive, readily produced, and efficient nozzle-header construction for this purpose which will first be described in connection with the accompanying drawings forming part of this 40 specification, and will then be more particularly pointed out in the claim.

In the drawings—

Figure 1 is a plan of a header embodying my invention in its preferred form.

Fig. 2 is a horizontal section of the same.

Fig. 3 is a cross section on line 3—3 Fig. 2.

Fig. 4, is a plan illustrative of the supply connections of the header.

Fig. 5 is a side elevation and

Fig. 6 is a front end elevation of the header.

In the drawings the nozzles-proper are indicated diagrammatically.

A is the header having the form of a 65 shallow rectangular box, and formed preferably of a single casting as shown, to which unitary construction the arrangement of its partitioned interior lends itself. The top of the header has substantially the 70 same area as the top of the crate; and the nozzles through which the fluid contents of the header are discharged, are divided into a plurality of sets, according to the different sizes of the bottles to be contained in 75 the crates, which sets of nozzles are distributed over the area of the top of the header to register with the particular sized bottles in connection with which they are to be used. In this instance the crates are 80 supposed to have either twelve or twenty bottle holding cells, for quarts and pints respectively, and the nozzles therefore are distributed over the area of the header-tops in two corresponding sets—twelve nozzles lettered *a* in the one set, and twenty nozzles lettered *b* in the other set, as shown clearly in Fig. 1. The quart nozzles *a* are arranged equidistant from one another in three rows 85 of four each lengthwise of the header and in four rows of three each crosswise of the header; and the pint nozzles are arranged equidistant from one another in four rows of five each lengthwise of the header and in five rows of four each crosswise of the 90 header—all the nozzles of both sets being, of course, so positioned as to be properly centered with reference to the crated bottles for which they are respectively intended.

The interior of the header is correspondingly divided by vertical partitions *p* into two separate and distinct sets of passage ways *c*, *d*, communicating the one with the feed inlet *C* and the other with the feed inlet *D*. The quart nozzles *a* open into the passage ways 105 *c*, and the pint nozzles *b* open into the passage ways *d*. Of the partitions *p* within the header, the outer partition, starting from the front end wall of header at a distance from the adjoining side wall to include the 110

inlet D for the pint passage-way *d*, thence extends continuously along that side wall, thence along the far end wall of the header, and thence returning along the other side 5 wall of the header until it reaches a point near the inlet C for the quart passage-ways *c* forming a continuous outer passage-way extending along three sides of the structure, but leaving an unobstructed entrance 10 passage from the inlet C to the area inclosed on three sides by the outer partition *p*, and on the fourth side by the end wall at the inlet end of the header. Within the thus inclosed area and extending longitudinally 15 thereof, but having no communication therewith, are two separate and distinct insular inclosures intended to serve as passage-ways for such of the pint nozzles *b* as are not in direct communication with the outer pint 20 passage-way, formed each by a single continuous oblong-shaped partition with parallel sides and rounded ends, the thus-formed inclosures being separated from one another and from the boundary walls of the 25 area in which they are located by intervals freely communicating with one another and forming the passage-ways with which the quart nozzles *a* communicate. Said inclosures are designed as passage-ways to directly communicate with such of the pint 30 nozzles *b* as are not in direct communication with the outer U-shaped pint passage-way *d*. In order to put these inclosures in communication with the pint inlet C, ducts 35 *e* are provided, which extend crosswise of the header on the under face of the bottom of header, communicating at their outer ends with the legs of the outer U-shaped pint passage-way *d*, through openings *e'* 40 and with the two inner separately inclosed pint passage-ways through openings, *e*², not only providing communication between these inclosures and the pint feed inlet C but also providing and assuring the utmost 45 freedom of circulation in all portions of the pint passage-way system. Similar freedom of circulation is obtained also in the quart passage-way system. The passage ways *c* for the fluid which is supplied to the quart 50 nozzles *a* and which as shown in Fig. 2 occupy that portion of the interior of the header not occupied by the pint passage ways *d*, are in free communication with one another and with their feed inlet C as indicated in the figure referred to. In Fig. 2 55 the small circles lettered *a* and *b* respec-

tively, and the horizontal and vertical lines lettered *m* at the intersections of which the circles are located, indicate diagrammatically the rows of nozzles *a*, *b* of the two sets, and the relations in which the individual members of the two sets stand to each other and to the partitions *p*. 60

The feed inlets may be controlled, as customary in apparatus of this kind, either by 65 a three-way cock common to both inlets, or by a separate cock for each inlet, the latter plan being represented in the drawing, wherein the inlets C D are provided each with its own cock. 70

Having described my improvement and the best way now known to me of carrying the same into practical effect, I state in conclusion that I do not limit myself narrowly to the structural details hereinbefore shown 75 and described, since manifestly the same can be varied to a considerable extent without departure from the spirit of the invention; but what I claim herein as new and of my own invention and desire to secure 80 by Letters Patent is as follows:

A nozzle header for bottle washing machines, comprising a hollow shallow box-like header body; partitions between the top and bottom thereof, dividing the interior of 85 the header into two sets of passage-ways, the one set comprising an outer continuous U-shaped passage-way on two sides and an intermediate end of the header, and, within the area not occupied by said outer passage-way, two additional passage-ways formed by oblong inclosures located therein at intervals apart from one another and from the walls which bound the area in which they are contained, and the other set comprising the passage-ways formed by intervals which separate said inclosures from 90 one another and from the walls of the area in which they are contained; cross-ducts extending between, and opening at their ends into the two legs of the U-shaped outer passage-way, and, at suitable points between their ends, into the two inclosures which are thus brought into communication each 95 with the other and with the outer passage-way: two sets of nozzles in the top of the header communicating with their appropriate sets of passage-ways: and a separate and distinct feed inlet for each set of passage-ways. 100

In testimony whereof I affix my signature.
WILLIAM W. BIRNSTOCK. 110
